Primary Examiner — Richard E Chilcot(74) *Attorney, Agent, or Firm* — Leason Ellis LLP**CLAIM**

The ornamental design for the refrigeration apparatus, as shown and described.

DESCRIPTION

1. Refrigeration apparatus

1.1 : Top left perspective view

1.2 : Top right perspective view

1.3 : Front

1.4 : Rear view

1.5 : Right side view

1.6 : Left side view

1.7 : Top

The broken line shown is for the purpose of illustrating portions of the refrigeration apparatus and forms no part of the claimed design.

1 Claim, 7 Drawing Sheets(56)
